UNITED STATES PATENT OFFICE.

PAUL C. BALDUS, OF MILWAUKEE, WISCONSIN.

VALVE-SETTING DEVICE.

1,402,391.

Specification of Letters Patent.

Patented Jan. 3, 1922.

Application filed July 26, 1920. Serial No. 398,952.

To all whom it may concern:

Be it known that I, PAUL C. BALDUS, a citizen of the United States, and resident of Milwaukee, county of Milwaukee, and State 5 of Wisconsin, have invented new and useful Improvements in Valve-Setting Devices, of which the following is a description, reference being had to the accompanying drawings, which are a part of this specification.

10 The invention relates to a device for adjusting the length of the valve rod for a valve of an internal combustion engine, and more particularly to valve rods used with overhead valve arrangements wherein the 15 adjustment of the valve is made between the valve rod and the overhead tappet lever.

It is now common practice to employ round rods for valve rods which are used in operating the valves of internal combustion 20 engines, and in order to adjust the length of this rod so that the valve will be properly actuated it is necessary to hold two parts of the rod in adjusted position while they are being tightened together, and to 25 do this requires the services of two men, one to hold the rod and the adjustable head while the other tightens up on the locking device. To overcome this difficulty, I have provided a device in which the operator may 30 successfully hold the round valve rod and the adjustable head in adjusted position with one hand while he secures them in position by screwing up a locking-nut with the other hand.

35 The invention further consists in the several features hereinafter set forth and more particularly defined by claims at the conclusion hereof.

The drawing shows a perspective view of 40 a device embodying the invention.

In the drawing the numeral 1 designates a round valve rod, 2 the adjustable spherically curved head mounted on the upper portion of the threaded end 3 of the rod 1 and provided with a wrench-engaging face 4, and 5 is the lock-nut mounted on the threaded portion 3 of the rod 1 and adapted to be screwed up against the head 2 and to lock said head and said rod in adjusted 45 position. As is well known, the rounded or spherical upper end of the head 2 engages in a similarly curved recess in the lever which acts upon the valve. All of this is of well-known construction and the tool 50 hereinafter described is designed to permit

of the adjustment of these parts by a single operator.

The device consists of a wrench 6 for engaging the wrench face 4 of the head 2, and a gripping tool 7 for the round rod 1, 60 such as a pair of pliers having jaws 8 and handles 9, the members of the pliers being pivotally secured together by a pivot bolt 10, and a connection between the wrench 6 and the tool 7 so that the device may be 65 readily held in one hand by the operator, the pliers holding the rod 1 and the wrench head 2 in fixed position so that a third wrench in the other hand of the operator may be applied to the nut 5. One of the 70 members of the pliers has a threaded opening 11 receiving a screw 12.

A slotted link 13, having one end journaled in the head 14 of the screw 12, is adjustably secured to the wrench by a screw 75 15 carried by the wrench 6 and passing through the slot in said link and provided with a clamping nut 16 to hold the link and wrench together when the wrench has been brought into engagement with the nut portion 80 4 of the head 2.

The pliers may be moved up and down upon the screw 12 so as to space the pliers from the wrench 6 at any desired distance to accommodate the position of these members 85 with respect to the parts to be engaged by them; and when adjusted the pliers are locked in spaced relation to the wrench 6 by means of a nut, such as a wing nut 17.

The wrench 6 is shown as a double-ended 90 wrench in which the wrench portions are of different sizes for accommodating different sized valve parts, and the screw 15 has a squared portion which fits the squared openings 18 near the ends of the wrench. 95

In the use of the device, the spaced adjustment of the wrench 6 and the gripping tool 7 is first effected so as to bring the jaws of the gripping tool in the plane of the rod below the nut 5 and the wrench in the plane 100 of the nut portion 4 of the head 2. The wrench 6 is at that time loosely connected to the link 13 so that it may be moved along the link or turned with respect to the link to bring the jaws of the wrench into proper 105 position with the faces of the nut 4, it being also noted that the link 13 is free to swing about the head 14 of the screw 12 to assist in this positioning of the wrench. The nuts 16 and 17 are tightened up, and while 110

the operator holds the device by gripping the pliers about the rod the wrench 6 engages the nut portion 4 of the head 2 so that both the rod and the head are held in adjusted position by one hand while with the other hand the operator takes another wrench and turns the nut 5 into locking engagement with the head 2.

I desire it to be understood that the invention is not limited to any specific form or arrangement of parts except in so far as such limitations are specified in the claims.

What I claim as my invention is:

1. The combination of a wrench, a round valve-rod engaging tool, and a connection between said wrench and tool to hold them in parallel spaced relation.

2. The combination of a wrench, a round valve-rod engaging tool, and an adjustable connection between said wrench and tool to hold them in parallel spaced relation.

3. In a device of the character described, the combination of a wrench, a pair of pliers, and means securing the wrench in spaced parallel relation to the pliers.

4. The combination of a wrench, a pair of pliers, a connection between the pliers and the wrench to hold them in spaced parallel relation with respect to each other and permit an angular adjustment of the wrench.

5. The combination of a wrench, a pair of pliers, a slotted link operatively secured at

one end to the pliers and at the other end to the wrench.

6. The combination of a wrench, a pair of pliers, and means for securing the wrench in spaced relation to the pliers, including a link and an adjustable screw.

7. The combination of a wrench, a round valve rod engaging tool, and linkage connecting the handles of said wrench and tool together permitting them to swing and move bodily relatively to each other, one end of said linkage having a spaced connection with one of the handles to dispose the wrench and the tool in parallel planes.

8. The combination of a wrench, a round valve rod engaging tool, and linkage connecting the handles of said wrench and tool together permitting them to swing and move bodily relatively to each other, one end of said linkage having an adjustable spaced connection with one of said handles to dispose said wrench and tool in parallel planes.

9. The combination of a wrench, a round valve rod engaging tool, a slotted link, means for adjustably clamping the slotted end of said link to the wrench, and means for connecting the other end of said link to the tool in spaced parallel relation therewith.

In testimony whereof I affix my signature.

PAUL C. BALDUS.
